UNITED STATES PATENT OFFICE.

JOSEPH BERGER, OF UTICA, NEW YORK, ASSIGNOR TO UNION SPECIAL MACHINE COMPANY, OF CHICAGO, ILLINOIS, A CORPORATION OF ILLINOIS.

OVEREDGE SEWING MACHINE.

Application filed July 30, 1924. Serial No. 729,100.

The invention relates to new and useful improvements in trimming mechanisms for sewing machines, and more particularly to a trimming mechanism which is adapted to trim an edge of fabric or the like in advance of an overedge stitching mechanism.

An object of the invention is to provide a trimming mechanism of the above character wherein the movable trimming blade is carried by a swinging arm which is relatively short and the pivot of which is disposed in the plane of the support for the fabric being trimmed.

A further object of the invention is to provide a trimming mechanism wherein the trimming blade moves from a point well above the fabric and the stationary blade down into cooperative action therewith and wherein means independent of the trimming blade is provided for yieldingly holding the movable blade in proper alignment for cooperation with the stationary blade.

A still further object of the invention is to provide a trimming mechanism of the above type with a trimming blade, the body of which is located in a plane inclined to the plane of the stationary blade, and wherein the cutting edge of the movable blade lies in a plane parallel with the stationary blade.

A still further object of the invention is to provide a movable trimming blade and a guide plate or bar which is associated therewith and which is carried by the mechanism which reciprocates the movable blade, and wherein said guide plate or bar is adjustable independently of the trimming blade and is adapted to bear continuously against the stationary trimming blade.

A still further object of the invention is to provide a sectional strip guide for guiding the trimmed off strip away from the stitching mechanism in rear thereof.

These and other objects will in part be obvious and will in part be hereinafter more fully disclosed.

In the drawings which show by way of illustration one embodiment of the invention—

Figure 1 is a front view of a sewing machine embodying my improvements;

Fig. 2 is a sectional view on the line 2—2 of Fig. 1;

Fig. 3 is a sectional view on the line 3—3 of Fig. 4;

Fig. 4 is an end view of a portion of the

machine, but with the cover plate swung out in order to disclose the operating parts in rear thereof;

Fig. 5 is an enlarged end view of a portion of the machine with the end of the cover plate in normal position;

Fig. 6 is a sectional view on the line 6—6 of Fig. 3;

Fig. 7 is a sectional view on the line 7—7 of Fig. 6; and

Fig. 8 is an enlarged detail in plan showing the presser foot, the cloth supporting plate, the movable trimming blade and the section of fabric which is being trimmed and the edge thereof covered by the stitching mechanism.

The invention is directed broadly to a trimming mechanism for a sewing machine, and more particularly to a trimming mechanism which is adapted to trim the edge of a fabric, which edge is subsequently covered by stitching. In carrying out the invention, the machine is provided with a cloth plate which supports the fabric to be trimmed and stitched. The edge is covered by a stitching mechanism which forms a series of connected thread loops extending around the edge to be covered. The material is fed across the cloth plate by a differential feeding mechanism consisting of two feed dogs one in advance of the stitching mechanism and the other in rear thereof, and these feed dogs are so operated that they may be given a differential movement relative to each other. The material is held on the cloth plate or work support by means of a presser foot which is provided with a yielding section. The cloth plate is carried by a supporting post rising from the bed plate of the machine at the forward side thereof. Mounted on this supporting post is a stationary member of the trimming mechanism. It is preferably arc-shaped, and the upper end thereof is provided with a cutting edge, and this cutting edge is located slightly below, but adjacent the upper surface of the cloth plate. Cooperating with this stationary cutting blade is a movable blade which is carried by an arm mounted on a shaft pivoted so as to swing

about an axis which lies in the plane containing the cloth plate. The arm is relatively short, so that the trimming member may be moved downwardly to cut the fabric with considerable force. The movable

blade is set at an incline to a plane containing the stationary blade and has its cutting face lying in a plane parallel with the outer face of the stationary blade. Said movable 5 blade swings from a position where it cooperates with the stationary blade to a position a considerable distance above the cutting edge of said blade. Said movable cutting blade is held in proper alignment for 10 cooperative action on the stationary blade by a guide or bar which is mounted to reciprocate with the movable blade and which maintains its contact with the stationary blade. Said bar or plate is yieldingly 15 pressed against the stationary blade by a spring which bears against the end of the shaft which carries this guide plate and also the movable cutting blade.

Referring more in detail to the drawings, 20 I have shown the invention as applied to a sewing machine having a bed plate 1 on which is mounted an overhanging arm 2 which carries a needle bar 3 at its outer end. Said needle bar is reciprocated by a needle 25 lever 4 pivoted at 5 on a bracket 6, and said lever is oscillated by means of an eccentric strap 7 cooperating with an eccentric 8 on the main shaft 9. The reciprocating needle bar 3 carries a needle 10. Cooperating with 30 the needle 10 beneath the work support is a thread carrying looper 11, which thread carrying looper 11 is rigidly carried by a short shaft 12 which in turn is mounted on a sleeve bearing 13 and is operated by a toggle 35 lever mechanism 14. Cooperating with the under looper 11 and the needle 10 is an overedge looper 15. This overedge looper 15 is actuated from a shaft 16 mounted in a bracket 17. The shaft 16 carries an arm 40 18 which is connected to an eccentric strap 19 cooperating with an eccentric 20 on the main shaft 9.

This stitching mechanism forms no part 45 of the present invention, but is shown, described and claimed in my co-pending application, Serial No. 729,099, filed of even date herewith.

The material to be trimmed is supported 50 by a cloth plate 21. The cloth plate 21 is supported in part by an upwardly extending bracket 22 which carries a lug 23. A screw 24 is threaded through the outer end of the cloth plate and into the lug 23.

The trimming mechanism consists of a 55 movable blade 30 and a stationary blade 26. This supporting bracket 22 is provided with an arc-shaped recess which receives the stationary trimming blade which is also arc-shaped. A clamping plate 27 overlies the 60 stationary blade and is drawn against the same by a clamping bolt 28 which is threaded through this bracket 22 (see Figures 4, 6 and 7). The upper edge of the stationary cutting blade is beveled as indicated at 29 (see Fig. 7). Cooperating with this sta-

tionary blade 26 is a movable blade 30. Said movable blade 30 as clearly shown in Fig. 7 is located in a plane which cuts the plane of the stationary cutting blade at an acute angle. The cutting edge of this movable 70 blade, however, which is indicated at 31, lies in a plane parallel with the front face of the stationary blade. This movable cutting blade is carried by an arm 32. The arm 32 is in turn carried by a sleeve 33 75 which is rigidly secured to a short shaft 34 by means of a set screw 35. This shaft 34 is mounted in spaced bearings 36 and 37 (see Figures 1 and 3). Mounted on the shaft between the spaced bearings is a collar 38 80 which carries an arm 39. At the upper end of the arm 39 is a ball stud 40 to which a link 41 is connected. This link 41 is connected at its other end to a ball stud 42 shown in dotted lines in Fig. 2. This ball 85 stud is carried by an arm 43 which is rigidly mounted on the shaft 16. As has been described above, this shaft 16 is oscillated by the eccentric strap 19, and as the shaft oscillates, it swings the arm 43 which moves the 90 link 41 endwise, and this in turn oscillates the shaft 34 carrying the arm 32. The upper end of the arm 32 is formed with a head 44. Said head 44 is provided with a recess 45 in which the movable trimming blade 30 95 is located. Said blade is held in this recess by a clamping plate 46 which is secured to the head by means of a clamping bolt 47. It will be noted from Figures 1 and 7 of the drawings that this movable blade 30 moves 100 from a position well above the stationary blade to a position where said movable blade performs a shearing cut in cooperation with said lower stationary blade. The cutting edges of the two blades are substantially 105 parallel and there is no guiding finger on the movable blade to limit the extent of the cutting action of the two blades, and furthermore, there is no guiding finger on the movable blade to interfere with the proper 110 sharpening of the blades. The two blades are maintained in proper alignment by an independent guide plate or bar 48 which is carried by the supporting head 44. Said head 44 is undercut as indicated at 49 in 115 Fig. 2, and the guide plate or bar 48 is mounted in this undercut portion as clearly shown in said figures. Said guide plate or bar is provided with a slot 50 through which a screw 51 passes to secure said plate or bar 120 to the head 44. This slot permits the guide plate or bar to be adjusted in a direction at right angles to the plane of the cooperating cutting blades. Inasmuch as it is independently mounted and separate from the cutting blade, it can be adjusted to properly align the blades without shifting the movable blade. It can also be set so as to prevent undue wear of the movable blade in its 125 shearing action with the stationary blade. 130

The shaft 34 which carries the movable blade is capable of endwise movement to a limited extent in the bearings 36 and 37 and is moved in a direction so as to hold this guide bar or plate in contact with the stationary blade or the parts in alinement therewith by means of a spring 52. Said spring 52 is fulcrumed at 53 on the stationary part of the machine and a threaded nut 54 carried by a screw 55 bears against the spring between its ends, and may be utilized for varying the tension of the spring on the shaft. This spring presses the shaft endwise toward the left as viewed in Fig. 1, and this endwise movement of the shaft is limited by the adjustable plate or bar 48.

The material to be stitched is held on the cloth plate 21 by means of a presser foot 56 and the material is fed across the cloth plate by means of feed dogs 57 and 58. These feed dogs are mounted so that one is located in rear of the needle and the other in front thereof, and said feed dogs may be given a differential feeding movement, if desired. The feeding mechanism forms no part of the present invention, but is shown, described and claimed in a co-pending application, Serial No. 729,101, filed of even date herewith.

The material to be stitched is indicated at F in the drawings (see Fig. 8), and the overedge stitches for covering the trimmed edge are indicated at S. In order to keep the trimmed off strip f from passing back and interfering with the stitching mechanism or the operating parts of the machine, I have provided a strip guide or cover plate 59. Said cover plate includes a vertical portion 60 which is hinged to the bed plate 1 by suitable hinges 61, 61. This cover plate as clearly shown in Figure 6 extends upwardly to form said vertical portion and is then inclined inwardly, and when in closed position, is adapted to bear against a supporting bracket 62. Said supporting bracket 62 is secured to the bracket 22 which supports the front end of the cloth plate, and also the stationary trimming member. Said supporting bracket 62 is provided with a laterally projecting portion 63 which is secured to the bracket 22 by means of a screw 63'.

Said strip guide is also provided with a movable section 64 (see Figures 2, 3, 6 and 7 of the drawings). This movable section is mounted on a supporting plate 65 which is formed as a part of the front cover plate 59, and is secured thereto by a pivot screw 66. The movable section 64 is spring pressed in an upward direction by means of a spring 67 which surrounds a rod 68 mounted on the inner face of the cover plate 59. The movable section of the cover plate is limited in its upward movement by a lug 69 carried by the supporting plate 65. Said

movable section may be moved downwardly against the tension of the spring 67 by means of a finger piece 70 (see Fig. 1).

It will be noted from Figures 2 and 6 of the drawings that this movable section of the cover plate extends to a point adjacent the cutting edge of the lower or stationary cutting blade and is located in behind the guide bar or plate 48. Inasmuch as the guide bar or plate 48 is located in front of the movable section 64 of the strip guide, said bar or plate will engage the trimmed off strip and positively force the same downwardly along the front face of the strip guide. Thus it is that this guide bar prevents the trimmed off strip from, in any way, working in behind the side edge of the strip guide and beneath the work support. When it is desired to uncover the parts in rear of the strip guide, the movable section is depressed through the aid of the finger piece carried thereby so as to move it from behind the guide bar or plate 48. Then the cover plate can be swung on its hinges 61 so as to uncover the parts in rear thereof. In Fig. 2 I have shown the combined strip guide and cover plate in its normal position for deflecting the trimmed off strip toward the front of the machine, and in dotted lines, I have shown this strip guide and cover plate as moved to a position to expose the parts in rear thereof. The cover plate 60 is held in closed position by means of a spring latch 71 attached to the bracket carrying the bearings 36 and 37. The cover plate has an integral finger piece 72 with a slot formed therein which takes over this spring latch.

It will be noted from Figures 3, 4 and 5 that the shaft which supports the movable trimming blade is substantially in the plane of the cloth plate and is in advance of the stitching mechanism. The arm 32 which carries the movable trimming blade is relatively short. This can be made short for the reason that the range of oscillation of the movable blade can be made relatively large, inasmuch as there is means for holding the movable blade and stationary blade in proper alinement. While I have described the trimming mechanism in conjunction with an overedge machine, it will be understood that it may be used with other types of stitching mechanisms.

While I have shown and described a differential feeding mechanism for moving the material across the cloth plate, it is obvious that, from certain aspects of the invention, the two feed dogs may be moved in unison, or a single feed dog of the ordinary construction may be used instead of the two feed dog differential feeding mechanism.

It is obvious that minor changes in the details of construction may be made with-

out departing from the spirit of the invention as set forth in the appended claims.

Having thus described the invention, what I claim as new and desire to secure by Letters-Patent, is—

1. A trimming mechanism for sewing machines comprising an upper movable trimming blade and a lower stationary cooperating blade, means for supporting and mov-

10 ing said upper blade from a position well above said stationary blade into cooperative cutting action therewith, and means independent of and movable with said movable blade for maintaining said movable blade in proper alinement with the stationary blade during the entire movement of said movable blade.

2. A trimming mechanism for sewing machines comprising an upper movable trimming blade and a lower stationary cooperating blade, means for supporting and moving said upper blade from a position well above said stationary blade into cooperative cutting action therewith, means independent 25 of said movable blade for maintaining said movable blade in proper alinement with the stationary blade, and means for yieldingly moving said movable cutting blade in a direction toward the stationary blade.

3. A trimming mechanism for sewing machines comprising an upper movable trimming blade and a lower stationary cooperating blade, means for supporting and moving said upper blade from a position well 35 above said stationary blade into cooperative cutting action therewith, and means independent of said movable blade for maintaining said movable blade in proper alinement with the stationary blade, during the entire 40 movement of said movable blade, said supporting means for the movable blade being constructed so that said movable blade extends at an acute angle to the plane of oscillation of the blade, the cutting edge of said 45 movable blade being beveled so as to lie in a plane coincident with the cutting face of the stationary blade.

4. A trimming mechanism for sewing machines including in combination, an upper trimming blade, a lower cooperating blade, a shaft extending at right angles to the cutting plane of said blades, an arm mounted on said shaft and having a trimmer head for supporting the movable trimming blade, 50 means for yieldingly pressing said shaft toward the stationary trimming blade, and means independent of the movable blade for limiting the endwise movement of said shaft and for maintaining said trimming blades in 55 cooperative cutting relation.

5. The combination with stitching mechanism; of a trimming mechanism, located in advance of the stitching mechanism and including a movable trimming blade and a stationary trimming blade, a shaft, a trim-

mer head mounted on said shaft and carrying said movable trimming blade, means for oscillating said shaft, yielding means for moving said shaft endwise for maintaining said trimming blades in cutting relation to each other, and means independent of the trimming blades for limiting the endwise movement of said shaft and maintaining said blades in proper alinement.

6. The combination with stitching mechanism; of a trimming mechanism located in advance of the stitching mechanism and including a movable trimming blade and a stationary trimming blade, a shaft, a trimmer head mounted on said shaft and carrying said movable trimming blade, means for oscillating said shaft, yielding means for moving said shaft endwise for maintaining said trimming blades in cutting relation to each other, means independent of the trimming blades for limiting the endwise movement of said shaft and maintaining said blades in proper alinement, and devices whereby said last-named means can be adjusted.

7. The combination with stitching mechanism; of a trimming mechanism located in advance of the stitching mechanism and including a movable trimming blade and a stationary trimming blade, a shaft, a trimmer head mounted on said shaft and carrying said movable trimming blade, means for oscillating said shaft, yielding means for moving said shaft endwise for maintaining said trimming blades in cutting relation to each other, and means independent of the trimming blades for limiting the endwise movement of said shaft and maintaining said blades in proper alinement, said movable blades being mounted on the trimmer head 105 so as to lie at an acute angle to the cutting plane and having its cutting face parallel with said cutting plane.

8. The combination with stitching mechanism; of a trimming mechanism having trimming blades located in advance of said stitching mechanism, movable means on which one of said trimming blades is mounted, said movable means being constructed so that said movable blade moves from a position well above said cooperating blade into cutting relation therewith, and means independent of said blades for maintaining the same in proper cutting alinement during the entire movement of said movable blade.

9. A trimming mechanism including in combination, a lower stationary cutting blade, an upper movable cutting blade, an oscillating arm on which said movable blade is mounted, said movable blade being set at an acute angle to the cutting plane and having its cutting face parallel with said plane, means for yieldingly pressing said movable blade toward the stationary blade for maintaining said blades in proper cutting rela-

tion, and adjustable means movable with said upper blade for maintaining said blades in proper alinement.

10. A trimming mechanism including in combination, a lower stationary cutting blade, an upper movable cutting blade, an oscillating arm on which said movable blade is mounted, said movable blade being set at an acute angle to the cutting plane and having its cutting face parallel with said plane, means for yieldingly pressing said movable blade toward the stationary blade for maintaining said blades in proper cutting relation, a guide bar movable with said upper blade and extending at right angles to the cutting plane for maintaining said movable blade in proper alinement with the stationary blade.

11. A trimming mechanism including in combination, a cloth plate, an adjustable stationary blade located beneath the cloth plate, an upper movable blade cooperating with said stationary blade, an oscillating shaft, an arm carried by said shaft and having a trimmer head on which said movable blade is mounted, said movable blade being set at an acute angle to the plane of oscillation thereof and having its cutting face located in said cutting plane, a guide bar carried by said trimmer head and extending at right angles to the cutting plane, means whereby said guide bar can be adjusted, and yielding means for moving the trimmer head so as to press said guide bar into contact with the stationary blade and thus maintain said cutting blades in proper cutting relation to each other.

12. A trimming mechanism including in combination, a cloth supporting plate, a lower stationary arc-shaped cutting blade, an upper movable cutting blade, a shaft, an arm carried by said shaft and supporting said movable trimming blade, said movable trimming blade being set at an acute angle to the plane of oscillation of said blade and having its cutting face parallel with said plane, a guide bar carried by said arm and extending at right angles to the cutting plane, and yielding means for forcing said shaft endwise and for holding said guide bar in contact with said stationary blade whereby said guide bar properly alines said cutting blades relative to each other.

13. A trimming mechanism including in combination, an upper movable trimming blade and a lower stationary trimming blade, a shaft located at the front of the machine, an arm carried by said shaft and extending rearwardly on which said movable cutting blade is mounted, means for oscillating said shaft, yielding means for moving said shaft endwise for maintaining the cutting blades in proper cutting relation to each other, and means independent of said movable trim-

ming blade for limiting the endwise movement of said shaft.

14. A sewing machine including in combination, a cloth plate, overedge stitching mechanism, a trimming mechanism located in front of said overedge stitching mechanism and including a lower stationary blade and an upper movable blade, a shaft at the front of the cloth plate and having a rearwardly projecting arm on which said movable blade is mounted, means for yieldingly moving said shaft in an endwise direction, a guide bar carried by said arm and adapted to engage the stationary blade for limiting the movement of the shaft so as to properly hold said blades in cutting relation to each other, a cover plate hinged at the front of the machine, a strip guide mounted on said cover plate and adapted to extend in rear of said guide bar so as to engage and deflect downwardly and forwardly the trimmed off strip, said strip guide being yieldingly mounted on the cover plate and adapted to swing about an axis coincident with the axis of the shaft carrying the movable trimming member whereby said strip guide can be lowered so as to permit the cloth plate to be swung in a forward direction to uncover the parts in rear thereof.

15. A sewing machine including in combination, a cloth plate, overedge stitching mechanism, a trimming mechanism located in front of said overedge stitching mechanism and including a lower stationary blade and an upper movable blade, a shaft at the front of the cloth plate and having a rearwardly projecting arm on which said movable blade is mounted, means for yieldingly moving said shaft in an endwise direction, a guide bar carried by said arm and adapted to engage the stationary blade for limiting the movement of the shaft so as to properly hold said blades in cutting relation to each other, a cover plate hinged at the front of the machine, a strip guide mounted on said cover plate and adapted to extend in rear of said guide bar so as to engage and deflect downwardly and forwardly the trimmed off strip, said strip guide being yieldingly mounted on the cover plate and adapted to swing about an axis coincident with the axis of the shaft carrying the movable trimming member whereby said strip guide can be lowered so as to permit the cloth plate to be swung in a forward direction to uncover the parts in rear thereof, and a yielding latch for holding said cover plate in closed position.

16. A trimming mechanism comprising a cloth plate, a supporting bracket for said cloth plate, trimming blades, means for supporting and operating the trimming blades so as to sever the fabric adjacent the edge of the cloth plate, a cover plate at the

front of the machine and having a depressed portion adjacent the edge of the cloth plate, and a strip guide pivotally mounted on the cover plate and normally 5 extending into said depressed portion and in rear of said trimming blades for deflecting the trimmed off strip toward the front of the machine.

17. A trimming mechanism comprising a cloth plate, a supporting bracket for said cloth plate, trimming blades, means for supporting and operating the trimming blades so as to sever the fabric adjacent the edge of the cloth plate, a cover plate at the front 15 of the machine and having a depressed portion adjacent the edge of the cloth plate, a strip guide mounted on the cover plate and extending into said depressed portion for deflecting the trimmed off strip toward the front of the machine, said strip guide being 20 pivotally supported by the cover plate, and a spring for normally swinging said strip guide in an upward direction to position the same for properly engaging the trimmed off 25 strip.

18. A trimming mechanism comprising a cloth plate, a supporting bracket for said cloth plate, trimming blades, means for supporting and operating the trimming blades so as to sever the fabric adjacent the edge of the cloth plate, a cover plate at the front of the machine and having a depressed portion adjacent the edge of the cloth plate, a strip guide mounted on the cover plate and extending into said depressed portion for deflecting the trimmed off strip toward the 30 35

front of the machine, said strip guide being pivotally supported by the cover plate, a spring for normally swinging said strip guide in an upward direction to position the 40 same for properly engaging the trimmed off strip, and a supporting ledge mounted on the support for the cloth plate against which said cover plate bears when in closed position.

19. A sewing machine including in combination a trimming mechanism having an upper movable trimming blade, a bar independent of and located beneath said movable trimming blade and movable with and operating to guide said trimming blade in its up and down movements, a strip guide located in rear of said bar so that the trimmed off strip is deflected downwardly by said bar in its up and down movements and positively caused to travel along the front face of said strip guide. 45 50 55

20. A sewing machine including in combination, a work support, trimming mechanism for trimming the edge of the fabric prior to the stitching thereof including co-operating trimming blades, a strip guide mounted at the edge of the work support for receiving and directing the trimmed off strip away from the trimming mechanism. 60 65 said trimming mechanism having a movable member independent of said trimming blades adapted to engage the trimmed off strip for positively directing the same against the front face of the strip guide. 70

In testimony whereof, I affix my signature.
JOSEPH BERGER.
